UNITED STATES PATENT OFFICE

HENRY A. LINDSLEY, OF CLEVELAND, OHIO

PACKAGE OF STACKED GASKETS

Application filed December 30, 1929. Serial No. 417,433.

This invention relates to a merchantable package of stacked, non-metallic gaskets maintained in stacked relation and protected from climatic size variations by a paraffin or other moisture-proof coating enclosing all or the side portion only of the stack.

A particular feature of the invention is the provision of means for enabling the number of gaskets desired for removal to be more easily and more accurately measured off, said means comprising suitable markers distributed along the stack at the desired intervals and dividing the stack into lots of any desired number, say twenty-five or fifty, said markers being of the same shape and size of said gaskets and being visible or conspicuous because of their contrasting color or otherwise.

A further feature of the present invention is the provision of means for enabling separation and removal of gaskets to be more easily and conveniently attained, said means comprising a suitable strip of paper or the like longitudinally disposed along the exterior side surface of the stack and preventing those portions of the gaskets lying therebeneath from being coated with the sealing material. By removing said strip, or any desired portion thereof, when all or a portion of the gaskets are desired for use, an uncoated stack portion is provided or exposed for convenient manipulation of the gaskets in effecting their separation.

Further features of the invention are in part obvious and in part will appear more in detail hereinafter.

The invention will be readily understood from the following description thereof, taken in connection with the accompanying drawings in which

Figs. 1 and 2 are respectively a side view and an end view of a gasket package made in accordance with one embodiment of the present invention; Fig. 3 is a perspective end view of a portion of a gasket package made in accordance with a slightly different embodiment of the invention and including means for exposing an uncoated portion of the stack of gaskets; Figs. 4 and 5 are perspective end views of an end portion of a gasket made in

accordance with the embodiment of the invention illustrated in Figs. 1 and 2 and including the exposing means of the Fig. 3 embodiment; said exposing means in Fig. 5 having a portion thereof in exposing position; and Fig. 6 is a side view of the package shown in Figs. 4 and 5.

The gaskets of the present package are made in various shapes and sizes, of oil or otherwise specially treated paper or paper composition. Being of such material, they are especially sensitive to climatic conditions, especially a moist condition, so that the lateral or cross size thereof frequently and materially varies, with consequent trouble and loss of time, especially if there is such variation when the gaskets are being used in factory assembly lines.

It has been customary heretofore to arrange, sell, ship and store such gaskets in stacks, say in stacks of two hundred or so, the gaskets being maintained in such stacked relation by paper strips longitudinally encircling the stacks, the ends of said strips being glued or otherwise suitably connected to each other. Aside from the trouble of applying these strips and interconnecting their ends, said strips have the objection that they must be broken or their ends disconnected if a portion only of the stack is desired, and in many places, just a few gaskets are needed at a time.

According to my invention, stacks of these gaskets are maintained in such stacked relation by paraffin or other moisture-proof sealing coatings enclosing all or the side portions only of the stacks. A more important purpose of these coatings, however, is to protect the gaskets from climatic changes, in order that there will be no variations in the size thereof.

The gaskets 10 of the package illustrated in Figs. 1 and 2 are of generally annular form, with each gasket provided with a circumferentially disposed series of bolt-receiving openings 12. The gaskets are held in stacked relation, and protected from climatic changes, by a sealing coating 14 of paraffin or other moisture-proof material. In this embodiment of the invention, said coating completely encloses the stack of gaskets, so that the inner and outer stack side walls, the walls of the 100

bolt-receiving openings 12, and the outer surfaces of the end gaskets are all covered with the coating material, with complete protection to the gaskets from climatic changes.

5 In the embodiment of the invention illustrated in Figs. 1 and 2, the coating solution is applied to the stack of gaskets, such as by a dipping operation, while said gaskets are held tightly together in stacked relation, with 10 the result that none of the coating solution flows between gaskets.

In the embodiment of the invention illustrated in Fig. 3, the gaskets 10a are loosely held in stacked relation during the dipping 15 operation to permit the coating solution to freely flow between gaskets, as at 15. As the result, all surfaces of each gasket are coated with the moisture-proof solution, with absolute protection from climatic changes for each 20 individual gasket, after its removal from the stack, as well as before.

In the embodiment of the invention illustrated in Fig. 3 and in the embodiment of the invention illustrated in Figs. 4, 5 and 6, the 25 gaskets 10a are of generally square shape, with centrally disposed circular openings 18 and bolt-receiving corner openings 20. The sealing coating, 14a in each embodiment, completely encloses the stack of gaskets, just as it 30 does in the embodiment of Figs. 1 and 2.

The embodiment of Fig. 3 and the embodiment of Figs. 4, 5 and 6 also each include means for providing, and exposing when desired, a longitudinally disposed uncoated portion of the stack, said means being more fully illustrated in the embodiment of Figs. 4, 5 and 6. Said means comprises a strip 25 of paper or the like longitudinally arranged or positioned along one corner of the stack and 35 preferably coextensive in length therewith. Said strip is arranged in place before the stack is dipped into the coating solution, so that the gasket portions beneath said strip are uncoated. By removing said strip, or a portion 40 thereof as in Figs. 5 and 6, said uncoated gasket portions are exposed and separation of gaskets is thereby rendered quick and easy.

For convenience and greater accuracy in 45 gauging or measuring off the number of gaskets desired, suitable markers 30 are distributed throughout the stack at any desired spacing or intervals, say at intervals of twenty-five or fifty. Said dividing markers may be rendered visible or conspicuous by being of contrasting color or otherwise, as will be readily understood.

If desired, the package of gaskets may be provided at its ends with suitable end members, of paper or the like and corresponding 50 in size and shape to the gaskets. The outer surfaces of these end members may bear any desired indicia or advertising legends and may be provided with or be free from the sealing coating, depending upon whether said 55 end surfaces are covered or uncovered when

the stack is immersed in the sealing or coating material.

I claim:

1. As a new article of manufacture, a stack of gaskets made of material which varies laterally in size in accordance with climatic conditions, a strip longitudinally arranged along the side of said stack, said stack having its side and said strip coated with a moisture-proof material which not only protects the gaskets of said stack from climatic changes but also maintains said gaskets in said stacked relation, said strip providing, upon its removal, a longitudinal uncoated portion of the stack which enables the gaskets to be more readily separated. 70

2. As a new article of manufacture, a stack of gaskets made of non-metallic material which varies in cross dimension in accordance with climatic conditions, the gaskets of said stack being of the same shape and the same cross dimensions and being maintained in stacked alignment by a moisture proof coating secured to the side surfaces of said stack, said coating not only maintaining said gaskets in such aligned, stacked relation, but also protecting said gaskets from size variation in response to climatic changes. 85

3. As a new article of manufacture, a stack of gaskets made of non-metallic material which varies in cross dimension in accordance with climatic conditions, the gaskets of said stack being of the same shape and of the same cross dimensions and each having a through opening, said gaskets being maintained in aligned stacked relation with said openings in alignment by a moisture proof coating secured to the side surfaces of said stack and to the stack surfaces surrounding said aligned openings, said coating not only maintaining said gaskets in such aligned stacked relation but also protecting said gaskets from size variation in response to climatic changes. 90

4. As a new article of manufacture, a stack of gaskets made of non-metallic material which varies in cross dimension in accordance with climatic conditions, the gaskets of said stack being of the same shape and of the same cross dimensions and each having a through opening and a through bolt-receiving aperture, said gaskets being maintained in aligned, stacked relation with said openings in alignment and said apertures in alignment by a moisture proof coating secured to the side surfaces of said stack and to the stack surfaces around said aligned openings and said aligned apertures, said coating not only maintaining said gaskets in such aligned, stacked relation, but also protecting said gaskets from size variation in response to climatic changes. 115

5. In testimony whereof I hereby affix my signature. 120

HENRY A. LINDSLEY. 120
